ATT'YS

UNITED STATES PATENT OFFICE.

ALBERT EDMUND HUDSON, OF CALGARY, ALBERTA, CANADA.

SPARK-ARRESTER.

1,347,374.

Specification of Letters Patent. Patented July 20, 1920.

Application filed October 13, 1919. Serial No. 330,191.

To all whom it may concern:

Be it known that I, ALBERT EDMUND HUDSON, a subject of the King of Great Britain, and a resident of the city of Calgary, in the Province of Alberta, in the Dominion of Canada, have invented certain new and useful Improvements in Spark-Arresters, of which the following is a specification.

This invention relates to improvements in spark arresters and fuel savers of that type particularly designed for use on locomotives, and the objects of the invention are to insert in the path of travel of the products of combustion a plurality of baffles which will extinguish sparks and arrest the same, and in this way assist in eliminating the danger of forest fires so common in some provinces wherein the timber or lumber becomes ignited from sparks emitted from passing trains.

Further objects are to permit of the spark arrester being formed sectional so that each section may be bodily removed as single unit for cleaning purposes or inspection and repair, and to so standardize the sections that they are readily fitted and interchangeable on standard locomotives at present in use with a minimum of time and labor.

Further objects still are to provide more room in the smoke box so that the spark arrester can be more readily positioned and removed when such is found necessary, and generally to adapt the several parts to better perform the functions required of them.

With the above and other objects in view the invention consists essentially of the improved constructions particularly described and set forth in the following specification and accompanying drawings forming part of the same.

In the drawings:

Figure 1 is a fragmentary longitudinal section of a locomotive boiler showing my improved spark arrester and extinguisher mounted in the smoke box.

Fig. 2 is a front view of the interior of a locomotive boiler showing the spark arrester and extinguisher in position.

Like characters of reference refer to the like parts in the several figures.

Referring to the drawings: A indicates a locomotive boiler of any usual description, in the smoke box of which a dead plate 10 is located just in front of the tube sheet 11.

The upper end of the dead plate 10 is lo-

cated behind the smoke stack 12, and the lower end of the dead plate is formed with a horizontal portion 13 which terminates at the front end in a downwardly extending flange 14, the said flange being spaced from the lower part of the smoke box.

The exhaust pipe 15 from the engine cylinders passes through the smoke box and has its upper end extending through the horizontal portions 13 of the dead plate 10, and above exhaust pipe and in alinement therewith are a pair of petticoat pipes 16 and 17, which are spaced from each other and from the exhaust pipe for an object which will be made clear hereafter.

Operatively supported from the horizontal portion 13 of the dead plate 10 and adjacent to the flange 14 is the spark arrester B.

This spark arrester B consists of a plurality of sections 19 each of box-like formation, being rectangular in cross section, and in the embodiment illustrated the sections are of a size sufficient to clear the smoke box door.

Each section 19 is provided with a plurality of baffle walls 21 extending transversely across the sections 19, the baffle walls 21 being formed of wire mesh, or perforated steel plate, each baffle wall being corrugated and spaced from the other, forming thereby a tortuous passageway through which the products of combustion must pass before being delivered to the up-take 12.

The baffle walls 21 are embraced between corrugated plates 22 located at the front and rear of each section 19, the plates 22 being formed with very fine perforations which, while permitting gases to enter the space between the plates 22 and the front and rear walls of the sections 19, will prevent sparks from lodging in this space. It will thus be clear that sparks cannot collect and smoulder and burn the plates on the corrugations of the plates 22.

Each section 19 is formed on the back wall with a flange 23 engaging with the upper face of the horizontal portion 13 of the dead plate, and a clamp 24 is carried by the dead plate to coact with the said flange to hold the sections of the spark arrester and extinguisher in position.

The front of each section of the spark arrester is formed with a downward depending flange 25 which engages with the rod 26 which extends across the smoke box, and the

flange 25 is secured to the rod 26 by means of thumb nuts and bolt 27.

Each section 19 of the spark arrester is open at the top and bottom allowing the free passage of the products of combustion through the said sections, and as the products of combustion travel through the sections, the sparks will be deflected backwardly and forwardly by the baffles and so extinguished. Any fine pieces of fuel carried in suspension by the products of combustion after leaving the upper end of the sections 19 will have been extinguished by the baffle walls 21, so that the smoke and products of combustion delivered to the smoke stack 19 will be free of sparks, etc.

The sections 19 are very quickly assembled in position and may be each bodily removed by undoing the thumb nut and bolt 27, and by unloosening the clamp 24, so that any broken parts may be quickly repaired with a minimum of time and labor. By forming the spark arrester in this way more clear

space is obtained in the smoke box than with other forms of spark arresters in use.

As many changes could be made in the above construction and many apparently widely different embodiments of my invention, within the scope of the claim, constructed without departing from the spirit or scope thereof, it is intended that all matter contained in the accompanying drawings, shall be interpreted as illustrative and not in a limiting sense.

What I claim as my invention is:

A spark arrester and extinguisher of the class described, comprising a removable section of box-like formation open at the top and bottom, a plurality of corrugated baffle walls in the section, and a pair of corrugated and finely perforated plates embracing the baffles and located against the front and rear walls of the section.

In witness whereof I have hereunto set my hand.

ALBERT EDMUND HUDSON
